MARKING RULE FOR DRAPERY PLEATING
Marvin Fink, Philadelphia, Pa., assignor to Colplete Corporation, Huntingdon Valley, Pa., a corporation of Pennsylvania
Filed Apr. 22, 1965, Ser. No. 450,000
9 Claims. (Cl. 33—103)

The present invention relates to new and useful improvements in apparatus for marking the location of pleats upon drapery material. More particularly, the invention relates to such a pleat marking rule as will mark both pleat spacing and the width or extent of the drapery material that forms each pleat.

Pinch-pleated draperies are presently in the mode for office and home decoration and require great skill and dexterity to properly compute and form the pleats therein. It has been found that the act of calculating the necessary dimensions to properly proportion the pleat spacing relative to the material that goes into the pleats is quite time consuming and this is true whether or not the finished drapery is made up of one, two, or more panels. It is frequently necessary for the drapery worker to take into consideration the fact that various panels of material frequently vary in width, primarily due to overlap in one end panel and the return or bend allowance in the other end panel. Hence, it may be seen that the calculations necessary to determine the number of pleats per panel and the proper spacing is one that must be carried out differently for each of the several panels forming the completed drapery. Matters may be further complicated in use of a panel of fractional width.

It is essential in marking pleats, that there be uniformity of the pleat spacing throughout the full width of the drapery regardless of whether one or a plurality of panels is utilized and whether or not a fractional sized panel is incorporated in the drapery. It is further of considerable importance to a quality finished drapery that the seams in multipanel draperies be hidden by placing the same immediately adjacent pleats so that the pleat and the folds formed thereby will hide the seams from ordinary view.

It is an object of the present invention to provide a marking rule for drapery layout and the like that will mark pleats while at the same time indicating proper pleat spacing.

Another object of this invention is to provide a new method of custom pleating draperies by the use of color indicia bands.

A still further object of the present invention is to provide a device that may be preset for the desired pleat spacing so that this spacing may be set and provide automatic pleat width marking in relation to the pleat spacing and according to the width of the drapery panel being marked.

Another important object of the present invention is to provide a marking rule having means to preset the offset of a central slide portion therein.

A still further object of the invention is to provide a marking rule for draperies and the like that may be conveniently installed on a drapery working table and has provision for proper alignment of one edge of the drapery material thereagainst.

Other objects of the invention are to provide a marking rule for draperies or the like bearing the above objects in mind, which is of simple construction, has a minimum number of parts, is inexpensive to manufacture, and is at all times efficient and accurate in use, and which will vastly reduce the time and hence cost in drapery manufacture.

For other objects and for a better understanding of the invention, reference may be had to the following detailed

2

description taken in conjunction with the accompanying drawing in which:

FIGURE 1 is a plan view of the marking rule of the present invention.

FIGURE 2 is a perspective of several of the various size spacer blocks or jigs used with the rule.

FIGURE 3 is a plan view of a set of tables used in conjunction with the marking rule, several of the sheets thereof being omitted for simplicity.

FIGURE 3A is a plan view of a complete sheet from the tables of FIGURE 3.

FIGURE 4 is an enlargement in plan of a portion of FIGURE 1 showing scale portion T in detail.

FIGURE 5 is a sectional view of the rule taken on line 5—5 of FIGURE 1.

FIGURE 6 is a sectional view of the rule taken along line 6—6 of FIGURE 1.

FIGURE 7 is a sectional view of the rule taken along line 7—7 of FIGURE 1.

FIGURE 8 is an enlarged plan view of one end of a modified form of the marking rule.

FIGURE 9 is a cross-sectional view taken along line 9—9 of FIGURE 8.

FIGURE 10 is a perspective view of one end of the preferred embodiment of the invention with a spacer block inserted in the well of the rule.

FIGURE 11 is a plan view of a layout of a curtain or drapery formed from several panels and showing the same in position on the marking guide with several pleat marks for the first panel having been made.

FIGURE 12 is a plan view similar to FIGURE 11, but showing the marking of the second panel.

Reference is now made more specifically to the drawings wherein similar parts have like reference characters throughout the several views and wherein the marking rule of the instant invention is designated generally at 10.

Marking rule 10 preferably comprises but two pieces of material, base 11 and slide 12. While aluminum or steel is preferred, the construction could obviously be fashioned from wood or plastic if desired. Extending from one side of and preferably formed integrally with base 11 is a sloping material support ramp 13. Ramp 13 joins base 11 at a point spaced slightly downward of the base upper surface 14 forming a shoulder 15.

The base 11 has a dovetail channel 16 formed therein throughout its length as shown in FIGURE 7 for mating reception of slide 12 which has its sides conforming in shape thereto. Holes 17 are provided at spaced selected points in channel 16 for receiving screws if it is desired to permanently secure the marking rule to the work table.

In order to secure slide 12 in selected offset position in channel 16, a central tapped hole 18 is formed in the slide which threadedly receives thumb screw 19. Tightening of the thumb screw will effectively lock slide 12 with respect to base 11.

In the preferred embodiment of the invention a generally rectangular well 20 is formed in channel 16 adjacent each end of the rule. Wells 20 are adapted to receive therein any one of a set of various size spacer blocks or jigs 21. These jigs are of sufficient height to interfere with movement of the slide and serve as an abutment for predetermined offset of the slide with respect to the rule as described in greater detail herein. Each of jigs 21 may have identifying indicia imprinted or stamped on the end faces thereof for ease in handling and are preferably stored in a compartmented case, not shown.

As an alternative means of achieving desired slide offset, slide 12 may be formed with rack teeth 22 on its underside as shown in FIGURES 8 and 9 and a pinion 23 mounted on a shaft 24 may be journaled in base 11 so that the pinion teeth mesh with rack teeth 22. A conventional knob 25 is fixed on shaft 24 and may be

operated to achieve the desired offset which is indicated on base scale 26 by a pointer 27 on slide 12.

Obviously many other mechanical means could be utilized to pre-set the rule and achieve offset such as worm gearing, axial screws, hydraulic piston-cylinder arrangements, wound cable drum, etc.

Scales are provided both on the upper surface 14 of base 11 and on the upper face of slide 12. As can be seen in FIGURE 1, these scales designated S, T, U, V, and W coincide when the rule is in its closed position with the ends of the base 11 and slide 12 flush. While all of the scales are essentially similar, scale T has been shown in detail in FIGURE 4.

The divisions of each scale section are uniform; i.e., the width between division lines is the same; however, the width of the scale segments increases from right to left as seen in FIGURE 1. In the preferred embodiment each of the areas in scale S is $\frac{1}{8}$ inch, in scale T $\frac{1}{4}$ inch, in scale U $\frac{3}{8}$ inch, in scale V $\frac{1}{2}$ inch, and in scale W $\frac{5}{8}$ inch.

In laying out the scales the distance between the beginning or index of each two adjacent scales is the same. If an overlap of scales results, such as between scales V and W, one or more of the scale segments may be omitted.

It is preferred that each scale segment be marked with easy to recognize indicia. As shown in FIGURE 4, each segment A, B, C . . . R on the slide 12 is painted with a different color. Similar colored bands are imprinted as shown on the upper surface of base 11. Although color bands are preferred due to ease in identification, letters, numerals, or any other desired indicia may be employed. In FIGURE 4 I have shown the use of both colored bands and letters.

It is to be understood that each of the scales S, T, U, V, and W, have the same indicia markings in the same order with the exception of overlapped scale areas as previously mentioned.

In use, in order to determine which of the jigs in the set are to be used, a set of tables 28 are provided, preferably comprising a plurality of overlapped pages 29, although the tables may be printed on a single sheet or even in book form if desired.

FIGURES 11 and 12 show in fragmentary fashion three drapery panels 31, 32 and 33 stitched together along the indicated seam lines. The drapery material is placed on ramp 13 with its finished side down and its buckram edge flush against the shoulder 15.

While I have shown only three panels of drapery material, it will be obvious that accordingly the panel width, i.e., thirty-six inches to fifty-four inches, and the width of the finished pleated drapery, as many panels as desired may be incorporated in a panel and even fractional-width panels may be utilized.

Even though adjacent panels may vary somewhat in dimension, no serious problem is presented and for practical purposes they will pleat up in the same manner. Typical pinch pleats comprise three folds of material gathered and stitched at their base. Since there are two small widths of material to each fold, the typical pinch pleat will have six such short material widths. Hence, the total amount of material in each pleat can vary considerably from one panel to another without making the difference noticeable. By way of example, if panel 32 is four inches wider than panel 31 due to an overlap or return at the outer edge thereof, then the material that goes into the pleats in panel 32 will be four inches more than the material in the pleats of panel 31. Assuming both panels are to have five pleats, the material in each pleat in panel 32 will be four-fifths of an inch wider than the material in each pleat of panel 31. Since we have seen that there are six short widths of material in each pleat, the depth of the pleats in panel 32 will be just a small fraction over one-eighth of an inch deeper than the pleat depth in panel 31. This, of course, cannot be visually detected except under the closest scrutiny.

The proper pleat spacing and the number of pleats are generally determined by the unpleated drapery material width in relation to the finished pleated drapery width. Generally, four, five or six pleats per full panel are used, but this can, of course, be varied dependent on the pleat depth and fabric width.

Once the operator has determined the overall size of pleated drapery required and the number of widths and pleats required, the proper page 29 in the table 28 is selected. With the pleated size known, the return and center space is ascertained from the center column. The third column gives a code number for the jig of spacer block 21 to be used. Alternatively the spacer block number may reflect a reading to be set on scale 26.

The rule slide 12 is then displaced and the selected spacer block is placed in either of the right or left wells 20. Determination as to which well is to be employed is dependent upon two factors; whether the panel is a right or left-hand panel, and the number of widths in the panel. 20 Most left-hand panels utilize the right well and most right-hand panels the left well. The lock screw 19 is then tightened.

All draperies have one more space than pleats regardless of the number of widths; for example, a three-panel drapery may have sixteen spaces and fifteen pleats counting the return and center as spaces. In order that two spaces do not fall together, one space must be measured off from each panel.

To facilitate use of the marking rule, all seams should be marked with chalk or pencil, or other marking device.

The center and return are then marked off utilizing the six inch scales 30 provided at each end of the rule.

Next, the left-hand edge of the drapery panel 31 is lined up with the left-hand edge of the base 11 as seen in FIGURE 11 except for left-hand panels of fractional widths or double widths. In these cases, the panel is displaced until the return mark as noted above is in line with the rule edge. This, in effect, measures off a space.

The operator must now visually determine the indicia color immediately adjacent the first seam as shown in FIGURE 11. This becomes the key color, and a visible mark is placed on the drapery material wherever this key color appears, either on the base upper surface 14 or on the slide scale 12. Since the first seam is at the joinder of the key color and the next zone, the visible marks are placed on the drapery material at the far end of the various key color bands. It will be seen that two separate mark spacings are thereby provided, one far pleat dimension and one for space between pleats.

Upon completion of the marking of the first width or panel 31, the material is displaced on ramp 13 as shown in FIGURE 12 until the first seam is in line with the edge of the rule base member. A space is marked off if indicated and a second key color corresponding to the position of the second seam is chosen. The material of the second panel or width 32 is marked in a manner similar to panel 31 wherever the second key color appears on the base member or slide.

A similar procedure is employed for all panels. When marking is completed, adjacent marks are stitched together forming pockets in the conventional manner.

It will be understood that the instant invention lends itself the calculating and marking of a wide variety of materials other than drapery fabric. It is indeed possible to use the disclosed invention for marking various spacings on lumber, sheet metal, plastics, etc.

The foregoing is deemed illustrative only of the principles of the invention. Further, since numerous modifications and substitutions of equivalents will readily suggest themselves to those skilled in this art, it is not desired to limit the invention to the exact construction described, and accordingly, all suitable modifications and equivalents may be resorted to, falling within the scope of the invention as claimed.

What I claim as my invention, and desire to protect by letters patent of the United States is:

1. A device to facilitate marking of material into selected dimensional widths with selected spacing between such widths comprising a generally flat base member, a slide moveable longitudinally with respect to said base member, a plurality of spaced scale sets on each of said base member and slide, each scale set having a plurality of scale segments, the segments in each set being of the same width, the segments in each scale set being of a greater width than the immediately preceding scale set and means to offset said slide with respect to said base member.

2. A device for computing the width and spacing of drapery pleats comprising an elongated, generally rectangular base member, an inclined material ramp attached to and coextensive with one longitudinal edge of said base member, a longitudinal groove defined by inclined side walls formed in said base member, a slide member slideably received within said groove, means to offset said slide member a selected distance with respect to said base member, a plurality of spaced scale sets on each of said base and slide members, each scale set having a plurality of scale segments, the segments in each set being of the same width, the segments in each scale set being of a greater width than the immediately preceding scale set, each of said scale sets having the same series of indicia, said scales on said base member and slide member being in alignment when the end of said slide member is in alignment with said base member.

3. A device as set forth in claim 2 wherein said indicia comprises different color bands for each of said segments.

4. A device as set forth in claim 2 wherein five scale sets are provided and the segment width of the first scale set is one-eighth inch, the second scale set is one-quarter of an inch, the third scale set is three-eights inch, the fourth scale set is one-half of an inch, and the fifth scale set is five-eighths of an inch.

5. A device for computing the width and spacing of drapery pleats comprising an elongated, generally rectangular base member, an inclined material supporting ramp integral with and coextensive with one longitudinal edge of said base member, a longitudinal groove formed in said base member, a slide member slideably received in said groove, a well formed adjacent each end of said base member and communicating with said groove, a selected one of a set of different size spacer blocks adapted to fit within one of said wells to offset said slide member with respect to said base member, a plurality of spaced scale sets on each of said base and slide members, each scale set having a plurality of scale segments, the segments in each set being of the same width, each of said scale sets having the same series of indicia, said scales on said base member and slide member being in align-

ment when the end of said slide member is in alignment with said base member.

6. A device as defined in claim 5 and further including an inch scale adjacent each end of said base member.

7. A device as defined in claim 5 and further including lock means carried by said slide member to secure said slide member in offset position on said base member.

8. A device to facilitate marking of material into selected dimensional widths with selected spacing between such widths comprising a generally flat base member, a slide movable longitudinally with respect to said base member, a plurality of spaced scale sets on each of said base member and slide, each scale set having a plurality of scale segments, the segments in each set being of the same width, means to offset said slide with respect to said base member, the base member being formed with a longitudinally extending groove, said slide being received in said groove for movement therein, a well formed adjacent each end of said base member and communicating with said groove, said means to offset said slide comprising a selected one of a set of different sized spacer blocks adapted to be received within one of said wells.

9. A device to facilitate marking of material into selected dimensional widths with selected spacing between such widths comprising a generally flat base member, a slide movable longitudinally with respect to said base member, a plurality of spaced scale sets on each of said base member and slide, each scale set having a plurality of scale segments, the segments in each set being of the same width, means to offset said slide with respect to said base member, the base member being formed with a longitudinally extending groove, said slide being received for movement within said groove, the means to offset said slide comprising a gear rack on the lower face of said slide, a pinion journaled in said base member and in mesh with said rack, means to turn said pinion, and an offset scale on said base member and a pointer on said slide.
